UNITED STATES PATENT OFFICE.

CHESTER F. JOHNSON, OF DETROIT, MICHIGAN.

CARBURETER.

1,213,499.

Specification of Letters Patent. Patented Jan. 23, 1917.

Application filed September 20, 1915. Serial No. 51,601.

To all whom it may concern:

Be it known that I, CHESTER F. JOHNSON, a citizen of the United States, residing at Detroit, in the county of Wayne and State of Michigan, have invented a new and useful Carbureter, of which the following is a specification.

In the use of carbureters having an auxiliary air valve, particularly those in which the tendency of the valve to open is resisted by a spring, considerable annoyance is experienced on account of fluttering of the valve to and from its seat at the lower engine speeds with throttle open—caused, probably, by the fact that the intake valve of the engine is set to allow admission of mixture even after the piston has reached the end of its suction stroke. The intake valve being open as stated (for the purpose of allowing a proper filling of the cylinder at intermediate and high speeds), the fresh mixture fills the cylinder relatively early in the cycle at low speeds and compression begins to be effective before the valve closes, which in turn causes a reversal of pressures in the mixing chamber and forces the valve back upon its seat.

The present invention has reference to a device whereby the said fluttering is prevented; it also possesses important advantages in that it allows more rapid acceleration of the engine, insures the formation of a more uniform mixture by avoiding pulsations in the mixing chamber, and renders the motor less subject to "spark knock" at low speed under conditions of high-compression early-spark. While the device is of special value when associated with an auxiliary air valve of a carbureter, the three last mentioned advantages are also present in those cases in which the carbureter has no auxiliary air valve, and it is to be understood, therefore, that the invention is not limited in all its features to carbureters of the type mentioned at the beginning of the specification.

The invention consists in a non-balanced auxiliary throttle valve located in the mixture passage, preferably at a point between the engine cylinder and the main throttle valve.

It further consists in an auxiliary throttle valve of this nature associated with the main throttle valve and with a valve for controlling the admission of auxiliary air; also in resilient means whereby opposition is

offered to the tendency of the air current to cause movement of the non-balanced auxiliary throttle valve; also in the details of construction shown, described and particularly pointed out in the claims.

In the drawings, Figure 1 is a vertical section through a carbureter in which one form of my invention is embodied. Fig. 2 is a fragmentary vertical section at right angles 65 to Fig. 1, showing the auxiliary throttle valve and controlling means therefor. Fig. 3 is a fragmentary elevation from the right side of Fig. 2.

Similar reference characters refer to like 70 parts throughout the several views.

The general features of the carbureter shown are quite similar to those disclosed in my United States Patent No. 1,095,212, dated May 5, 1914, and comprise a body 1 75 flared at its lower end 2 for attachment, by means of screws 3, to a float chamber, cover 4. The latter is provided with the upstanding annular flange 5 and has its central portion depressed at 6 and threaded to receive 80 the nozzle 8 which extends down into the float chamber 9 that is secured thereto and clamped to the cover by the screw 10. Fuel is admitted to the float chamber through the passage 11, the flow being controlled by a 85 valve 12 and float 13. Interposed between the body and the cover 4 and spaced from the latter, is a diaphragm 14, through the central portion of which the strangle tube 15 depends. The flange 5 is provided with 90 openings 16 for the admission of primary air.

The body 1 is extended laterally to form a valve chamber 18 to which auxiliary air is admitted through an opening 19, upon the 95 edge of which the auxiliary air valve 20, pivoted at 21, is adapted to seat. A spring 22 tends to hold the valve upon the seat, and means, indicated as a whole by 23, is provided for regulating the tension of the 100 spring. Positioned in the mixture passage is a main throttle valve 25 that is actuated by a throttle lever (not shown). The above described elements are substantially the same as those disclosed in my prior patent, 105 and are shown merely for the purpose of illustrating an approved general relation of parts.

Extending transversely across the mixture passage, preferably at a point between 110 the cylinder of the engine and the throttle valve 25, is an auxiliary throttle shaft 26

which may be slotted to receive an auxiliary throttle valve of the automatic type as shown, one side 28 of which is of somewhat greater area than the other side 29, the precise shape and relation of the sides being susceptible to considerable variation. As shown, the valve is cut away near the ends of the valve shaft to allow the use of washers 30, the surfaces 31 of which are preferably spherical (the body 1 being cylindrical at this point). One end of the shaft 26 projects through the wall of the body into a hollow boss 32, with reference to which a clamping plate 33 may be adjusted by the screws 34. Interposed between the clamping plate and a shoulder 35 on the boss is a tension-regulating nut 36 to which one end of a spring 38 is secured in any desired manner, its opposite end being soldered or otherwise attached to the end of the shaft 26. The clamping plate is perforated at 39 to allow access of a screw driver to the nut 36. A pin 40 (Fig. 1) which projects through the wall 25 of the mixture passage, may be used to limit the movement of the auxiliary throttle in a counter-clockwise direction; and by placing the point of a spring scale in the depression 41 formed in the upper face of the side 29 of the auxiliary valve, the amount of stress to which the spring 38 is subjected at any time may be readily determined, whereby the proper initial adjustment may easily be made.

35 While I have shown spring means for closing the valve 28-29, a similar result may be secured by so proportioning the sides of the valve that the product of the weight of one side multiplied by the distance of the center of gravity of the side from the axis of the throttle shaft is greater than the product of the corresponding weight and distance for the other side.

45 Operation: The auxiliary throttle valve stands in the position shown when the main throttle valve is closed. As the latter is opened, the air current causes the auxiliary throttle valve to gradually swing in a clockwise direction toward the longitudinal central plane of the mixing chamber; and its gradual response to the air current tends to prevent the lagging of the motor caused ordinarily by a sudden opening of the main throttle in accelerating from low speed 50 when the motor is cold. It also tends to prevent surging or pulsation of the mixture back and forth in the mixture passage which insures a more uniform mixing of the fuel and air than otherwise takes place, and, it appears, does away largely with the annoying metallic sounds that occur, particularly in the larger motors, at low speed 55 when the spark is made too early in the cycle. These effects are also coupled with 60 the dampening or flutter-preventing action

on the auxiliary air valve, heretofore mentioned.

It will be observed that there are two non-balanced valves controlling the air and gas incoming to the motor, the first, 20, serving to control the quality of the mixture and the second, 28-29, controlling the quantity.

It is clear that many changes may be made in the details of construction without departing from the spirit of my invention; for example, the auxiliary throttle valve may be located in the manifold of the engine rather than in the carburetor body. I do not, therefore, wish to be limited otherwise than as indicated by the subjoined claims.

I claim:

1. Means for feeding a combustible mixture to an internal combustion engine comprising means for forming a mixture passage, means for supplying air to the mixture passage, means for supplying fuel to the mixture passage, a main throttle valve located in the mixture passage, and an auxiliary pivotally mounted non-balanced throttle valve also located in the mixture passage.

2. Means for feeding a combustible mixture to an internal combustion engine comprising means for forming a mixture passage, means for supplying air to the mixture passage, means for supplying fuel to the mixture passage, a main throttle valve located in the mixture passage, and an auxiliary non-balanced throttle valve located in the mixture passage at a point between the cylinder of the engine and the main throttle valve.

3. Means for feeding fuel to an internal combustion engine comprising means for forming a mixture passage, means for supplying air to the mixture passage, means for supplying fuel to the mixture passage, a main throttle valve located in the mixture passage, an automatic pivotally mounted throttle valve also located in the mixture passage, said automatic throttle valve being arranged to be moved in one direction by the in-rushing fuel mixture, and resilient means tending to resist the movement of said valve.

4. Means for feeding fuel to an internal combustion engine comprising means for forming a mixture passage, means for supplying air to the mixture passage, means for supplying fuel to the mixture passage, a main throttle valve located in the mixture passage, an auxiliary throttle shaft extending transversely across the mixture passage, an automatic throttle valve carried by the shaft, the portion of the last mentioned valve on one side of its shaft offering greater resistance to a current in the mixture than the portion on the other side of the shaft, and

resilient means tending to hold the automatic throttle valve in such position as to partly close the mixture passage.

5. Means for feeding fuel to an internal combustion engine comprising means for forming a mixture passage, means for supplying air to the mixture passage, means for supplying fuel to the mixture passage, a main throttle valve located in the mixture passage, an auxiliary throttle shaft extending transversely across the mixture passage, an automatic throttle valve carried by the shaft, the portion of the last mentioned valve on one side of its shaft offering greater resistance to a current in the mixture than the portion on the other side of the shaft, resilient means tending to hold the automatic throttle valve in such position as to partly close the mixture passage, and means for varying the resistance which the resilient means offers to movement of the valve.

6. Means for feeding fuel to an internal combustion engine comprising means for forming a mixture passage, means for supplying air to the mixture passage, means for supplying fuel to the mixture passage, a main throttle valve located in the mixture passage, an auxiliary throttle shaft extending transversely across the mixture passage 25 at a point between the throttle valve and the engine cylinder, an automatic throttle valve carried by the shaft, the portion of the last mentioned valve on one side of its shaft offering greater resistance to a current in the mixture than the portion on the other side of the shaft, and resilient means tending to hold the automatic throttle valve in such position as to partly close the mixture passage.

7. Means for feeding fuel to an internal combustion engine comprising means for forming a mixture passage, means for supplying a mixture of fuel and primary air to the passage, means for supplying auxiliary air to the passage, said last mentioned means including an auxiliary air valve, a main throttle valve located in the passage, and an automatic non-balanced throttle valve also located in the mixture passage, whereby fluttering of the auxiliary air valve is avoided.

8. Means for feeding fuel to an internal combustion engine comprising means for forming a mixture passage, means for supplying a mixture of fuel and primary air to the passage, means for supplying auxiliary air to the passage, said last mentioned means including an auxiliary air valve, a main throttle valve located in the passage, an automatic non-balanced throttle valve also located in the mixture passage, and resilient means tending to hold the automatic throttle valve in such position as to partly close the mixture passage, whereby fluttering of the auxiliary air valve is lessened or avoided.

9. Means for feeding fuel to an internal combustion engine comprising means for forming a mixture passage, means for supplying a mixture of fuel and primary air to the passage, means for supplying auxiliary air to the passage, said last mentioned means including an auxiliary air valve, a main throttle valve located in the passage, an automatic non-balanced throttle valve also located in the mixture passage, resilient means tending to hold the automatic throttle valve in such position as to partly close the mixture passage, whereby fluttering of the auxiliary air valve is avoided, and means for varying the tension of the resilient means.

10. Means for feeding fuel to an internal combustion engine comprising means for forming a mixture passage, means for supplying a mixture of fuel and primary air to the passage, means for supplying auxiliary air to the passage, said last mentioned means including an auxiliary air valve, a main throttle valve located in the passage, a shaft for an automatic throttle valve located in the passage, a non-balanced automatic throttle valve carried by the shaft, the means for forming a mixture passage including a hollow boss, said shaft projecting into the boss, and a spring secured to the shaft and concealed in the boss whereby the automatic throttle valve is normally held in position to retard the flow of fluid through the passage.

11. Means for feeding fuel to an internal combustion engine comprising means for forming a mixture passage, means for supplying a mixture of fuel and primary air to the passage, means for supplying auxiliary air to the passage, said last mentioned means including an auxiliary air valve, a main throttle valve located in the passage, a shaft for an automatic throttle valve located in the passage, the means for forming a mixture passage including a hollow boss, a non-balanced automatic throttle valve carried by the shaft, said shaft projecting into the boss, a spring secured to the shaft and concealed in the boss, a clamping plate carried by the boss, a nut interposed between the clamping plate and the boss and secured to the spring, whereby the automatic throttle valve is normally held in position to retard the flow of fluid through the passage.

12. Means for feeding fuel to an internal combustion engine comprising means for forming an intake passage leading to the engine, means for feeding fuel to the passage, and two non-balanced valves located in the passage, one controlling the quality and the other controlling the quantity of the mixture delivered to the engine.

13. Means for feeding a combustible mixture to an internal combustion engine comprising means for forming a mixture pas-

sage, an automatic valve in said passage, means for supplying fuel to the mixture passage, and an automatic non-balanced throttle valve located in the mixture passage.

5 14. Means for feeding a combustible mixture to an internal combustion engine comprising means for forming a mixture passage, an automatic valve in said passage, means for supplying fuel to the mixture passage, and an automatic throttle valve located in the mixture passage.

10 15. Means for feeding fuel to an internal combustion engine comprising means for forming a mixture passage, means for sup-

15 plying a mixture of fuel and primary air to the passage, a main throttle valve located in the passage, a shaft for an automatic

throttle valve located in the passage, a non-balanced automatic throttle valve located in the passage, the means for forming the mixture passage including a hollow boss, a non-balanced automatic throttle valve carried by the shaft, said shaft projecting into the boss, a spring secured to the shaft and concealed in the boss, a clamping plate carried by the boss, a nut interposed between the clamping plate and the boss and secured to the spring, whereby the automatic throttle valve is normally held in position to retard the flow of fluid through the passage.

20 25 30 In testimony whereof I sign this specification.

CHESTER F. JOHNSON.
